The characteristic features of our new design reside in the formation of the back supporting strap between the side rails at the upper end of the chair back and in the lower angular edges of the side rails of the seat along with the form of connecting brace between the rail legs of the chair.

We claim:

The ornamental design for a folding chair, substantially as shown and described.
